DESIGN FOR A TILE

William W. Kellogg, Los Angeles, Calif.

Application December 6, 1933, Serial No. 49,973

Term of patent 14 years

To all whom it may concern:

Be it known that I, WILLIAM W. KELLOGG, a citizen of the United States, residing at Los Angeles, in the county of Los Angeles and State of California, have invented a new, original, and ornamental Design for a Tile, of which the following is a specification, reference being had to the accompanying drawing, forming part thereof.

I claim:

The ornamental design for a tile, as shown.

WILLIAM W. KELLOGG.
